UNITED STATES PATENT OFFICE.

LEOPOLD NEWMAN, OF BRADDOCK, PENNSYLVANIA.

MACHINE FOR FINISHING BOTTOM ENDS OF TROUSERS-LEGS.

SPECIFICATION forming part of Letters Patent No. 590,585, dated September 28, 1897.

Application filed June 23, 1896. Serial No. 596,595. (No model.)

To all whom it may concern:

Be it known that I, LEOPOLD NEWMAN, a citizen of the United States, residing at Brad-
dock, in the county of Allegheny and State of
Pennsylvania, have invented certain new and
useful Improvements in Apparatus for Fin-
ishing the Bottoms of Trouser-Legs; and I
do declare the following to be a full, clear, and
exact description of the invention, such as will
enable others skilled in the art to which it
appertains to make and use the same, refer-
ence being had to the accompanying draw-
ings, and to the figures of reference marked
thereon, which form a part of this specifica-
tion.

This invention relates to an improved means
for sealing and finishing the turned-in por-
tion of trousers-legs.

The object of my invention is to provide a
device that will effectually heat or melt the
gum tissue used to secure the parts together
and at the same time roll or press the parts
together. In the means heretofore employed
it required a skilled hand and the use of a
smoothing-iron to properly secure the parts
together and causing considerable loss of
time.

With the above objects in view the invention
consists in the novel construction, com-
bination, and arrangements of parts to be
hereinafter more specifically described.

In describing the invention in detail refer-
ence is had to the accompanying drawings,
forming a part of this specification, and where-
35 in like figures of reference indicate simi-
lar parts throughout the different views, in
which—

Figure 1 is a back view of the machine.
Fig. 2 is a side view of the same with a por-
tion of the housing broken away. Fig. 3 is
a central longitudinal sectional view. Fig. 4
is a cross-section on the line $x-x$ of Fig. 3.

In the said drawings the reference-numeral
1 designates the base of the machine, prefer-
ably made of cast metal, and having integral
therewith two parallel upwardly-extending
standards or uprights 2. Located between
said uprights and supported upon the upper
end of the said base is a half-round box 5,
upon which rests a corresponding half-round
box 4. These two boxes form the bearing for
a solid roller 4', projecting laterally from one

side of said uprights and having the outer
end pointed, as seen in Fig. 2. The inner end
of this roller is formed with a peripheral 55
groove 5', with which the inner or semicyl-
indrical sides of the said boxes engage. Located
above said boxes are similar boxes 6 and 7,
forming a bearing for a hollow roller 8, which
is also formed with a peripheral groove 8' to 60
receive the boxes. The said boxes are formed
with flanges 3', which engage with the sides
of the uprights, whereby the boxes are held
in place. Located above said roller 8 and
supported between the said uprights is a wa- 65
ter-receptacle 9, formed at its upper end with
two lugs 10, in which is journaled a trans-
verse shaft or rod 10', to the ends of which is
secured a cam-lever 11, the free ends of which
levers are connected by a handle 12, by which 70
they are operated. The inner ends of the said
levers are formed with cams 12', which en-
gage with the upper ends of the uprights 2
when the levers are depressed to elevate
the water-receptacle and relieve the hollow 75
roller of the pressure of the same. The nu-
meral 13 designates a gas-pipe leading from
a gas-supply, and when the gas issuing from
the end thereof is lighted the roller into which
said pipe extends is heated to the desired 80
temperature. Secured to one end of the said
roller 8 is a cog-wheel 14, which meshes with
a corresponding cog-wheel 15, secured to the
roller 4'. This cog-wheel 15 is provided with
an operating-crank 16. 85

The operation is as follows: The ends of the
pantaloons or trousers legs are turned up and
gum tissue inserted between such turned-up
ends and the portion of the leg to which they
are to be secured, in the usual manner. The 90
gas-pipe is then lighted to heat the roller 8
and the levers 11 depressed so as to elevate
the water-receptacle. The turned-up ends of
the trousers-legs can then be inserted be-
tween the two rollers, when the levers are 95
again elevated, so that the water-receptacle
will press down upon the hollow roller 8. By
now rotating the said rollers by means of the
cog-wheels the gum tissue will be melted and
the turned-up ends of the trousers-legs caused 100
to adhere to the leg portion. By my inven-
tion a great saving in time and money is ef-
fected over the old manner of finishing with
a smoothing-iron by hand.

Having thus fully described my invention, what I claim is—

In a machine for finishing and sealing the turned-up ends of trousers-legs, the combination, with the base, the parallel uprights or standards, the half-round boxes forming bearings for the solid and hollow rollers, located between said uprights and formed with end flanges, engaging with the sides of the uprights, and the solid pointed roller and the hollow roller journaled in said bearings and formed with peripheral grooves, with which the said boxes or bearings engage, of the intermeshing cog-wheels secured to said rollers,

the gas-pipe extending into the said hollow roller, the water-receptacle located above the hollow roller, the lugs at the upper end thereof, the transverse shaft journaled in said lugs, the cams and cam-levers secured thereto, and the handle connecting the free ends of said levers, substantially as described.

In testimony whereof I affix my signature in presence of two witnesses.

LEOPOLD NEWMAN.
